UNITED STATES PATENT OFFICE.

FERNANDO H. KAHN, OF SAN FRANCISCO, CALIFORNIA.

LENS-FASTENING.

1,132,945.

Specification of Letters Patent. Patented Mar. 23, 1915.

Application filed December 9, 1914. Serial No. 676,206.

To all whom it may concern:

Be it known that I, FERNANDO H. KAHN, a citizen of the United States, and resident of San Francisco, in the county of San Francisco and State of California, have invented certain new and useful Improvements in Lens-Fastenings, of which the following is a specification.

This invention relates to lens fastenings and my improvement is directed particularly to a means of rigid connection between lens and mount which is not dependent upon degree of tensional grip for the security of the union effected.

With the usual form of lens mount fastenings, as where the strap portions are united by a screw passed through the lens, loosening thereof occurs as the lens works upon said screw, involving considerable annoyance to the wearer from the frequent occasion to tighten the screw; besides causing variation in the adjustment of the lens, detrimental to the user's field of vision.

The main pre-requisite for the connection between a lens and its mount is that by its means said elements shall become so interconnectingly engaged as to be a practically homogeneous structure, and thus incapable of disengagement or loosening at the joint.

With this object in view, my invention consists of a mount having strap portions to lie against opposite sides of a lens, inclosing a slot extending longitudinally within the lens, the said mount having a rigid tongue lying between the straps within the slot in the lens, and cement or other plastic adherent or hardening substance, molded between the tongue and the slot, to securely bind and thus anchor the mount to the lens.

The lens slot may be enlarged inwardly, and the tongue may have an enlarged portion to lie within said slot enlargement, so that when provided with the cement filling or the like embedding the tongue and locking its enlargement as in a cast, withdrawal and oscillation are positively prevented.

The tongue of the mount, which is in the form of a web between the two strap portions, may be separated from one of said strap portions by a clearance space, to enable the straps to accommodate lenses of varying thickness, within certain limits, or of varying surface contour, and to provide space for inward bending of one of said

strap portions into close contact with the adjacent lens surface.

Other features and advantages will hereinafter appear.

In the drawing: Figure 1 is a partial plan view of a lens with mount attached. Fig. 2 is an enlarged section through the lens and mount. Fig. 3 is a cross section on the line 3-3 of Fig. 2. Fig. 4 is a perspective view of the mount, and Fig. 5 is a detail view of a modification.

In carrying out my invention, a lens, as 1, has a slot 2 extending therein from one end in the form of a longitudinal notch, of sufficient depth to receive a tongue or key 3 extending from a mount 4 provided with 70 strap portions 5, 6. The slot 2 may have an enlargement 7, and the tongue 3 may have an enlarged terminal portion 8, to lie within said enlargement 7; whereby, when a filling of cement or the like is provided for the slot 75 2 and its enlargement, the tongue aforesaid becomes securely bound therein, the cement or the like being locked against withdrawal within the slot, because the mass of the cement is provided with a head portion within enlargement 7, while the enlarged terminal portion 8 of the tongue is similarly locked, by embedment within the cement or the like.

The strap portions 5 and 6 respectively 85 lie over the opposite sides of slot 2, in contact with the lens surfaces about the slot edges, but said strap portions do not exercise tensional pressure upon the lens, merely serving as inclosing side walls for 90 the cement filling, and for laterally localizing the amount upon the lens.

A clearance, as at 9, may be left between the tongue 3 and one of the strap portions, as 5, permitting the latter to be bent inwardly upon a lens surface that fails to fill out the full space between the straps. In this way varying thicknesses and surface contours of lenses may be accommodated between the straps, while permitting the latter to lie snugly upon the lens surfaces. But it must be particularly noted that the lens straps exert no binding or securing tension upon the lens, which is, under the system of mount connection herein shown, 100 subject to no bearing strains whatsoever.

In practice the slot 2 is filled with cement or other suitable plastic adherent or harden-

ing substance, and the mount is then placed in position with the tongue 3 entered and embedded therein and the strap portions covering the slot at the lens sides, whereby, 5 upon hardening of the cement or the like, the lens and mount become unified as a homogeneous solid, without pressure or strain or other liability of weakening the lens at or near its point of connection with 10 the mount.

In a modified form of the aforesaid mount, as in Fig. 5, the enlargement 10 of the tongue may be in cylindrical form, axially pierced and threaded, and the strap portion 11, separated from said tongue, may have an alined orifice 12 for the reception of a screw 13, to further connect said strap portion and tongue.

Variations may be resorted to within the 20 scope of my invention, and portions thereof used without others.

I claim:

1. The combination with a lens having a longitudinal slot, of a mount with strap portions 25 embracing said lens to inclose said slot, a tongue extending from said mount into said slot, said tongue lying between said strap portions, with an intervening clearance, and a hardening substance to unite said tongue and lens within said slot.

2. The combination with a lens having a longitudinal slot with an inner enlargement, 30 of a mount with strap portions embracing said lens to inclose said slot, a tongue extending from said mount into said slot with an enlarged portion to lie in said slot enlargement, said tongue also lying between

said strap portions with an intervening clearance, and a hardening body to unite 40 said tongue and lens within said slot.

3. The combination with a lens having a longitudinal slot with an inner enlargement, of a mount with strap portions embracing said lens to inclose said slot, a tongue connected to and extending from said mount 45 into said slot with an enlarged portion to lie in said slot enlargement, between said strap portions, with an intervening clearance, one of said straps and said tongue enlargement having alined thread orifices, a screw engaged in said orifices to connect 50 said strap and tongue, and a hardening substance to unite said tongue and lens within said slot.

4. The combination with a lens having a longitudinal slot with an inner enlargement, 55 of a mount with strap portions embracing said lens to inclose said slot, a tongue connected to and extending from said mount into said slot with an enlarged portion to 60 lie in said slot enlargement, between said strap portions, with an intervening clearance, one of said straps and said tongue enlargement having alined thread orifices, and a screw engaged in said orifices to connect 65 said strap and tongue.

Signed at the borough of Manhattan, in the city, county, and State of New York, this 8th day of December, A. D. 1914.

FERNANDO H. KAHN.
